UNITED STATES PATENT OFFICE

2,224,128

WINDING MACHINE

Edward J. Abbott, Wilton, N. H., assignor to Abbott
Machine Company, Wilton, N. H., a corporation
of New Hampshire

Application February 25, 1935, Serial No. 8,013

6 Claims. (Cl. 242—35.5)

This invention relates to traveling spindle winders, and is of particular applicability to traveling spindle winders for producing headless cross-wound packages of yarn and the like. In the past, winding machines of this type have involved the use of traverse elements which are moved to and fro in proximity to the winding package for laying the yarn into the desired quickpitch spiral formation on the packages during travel of the packages around the machine. Thus my Patent No. 1,609,639 discloses the inclusion on the traveling winding unit of a vertical oscillating arm of which the upper end is adapted to serve as a guide eye for the yarn near the face of the winding package. The Reissue Patent No. 18310 to Edward J. Abbott and William J. Abbott, Jr., discloses the provision on the traveling unit of a reciprocating slider carrying a guide eye for traversing the yarn.

For certain types of yarn and certain conditions of winding it is advantageous to employ traversing means of a type which does not involve the use of reciprocating or oscillating parts. In cases where the yarn can be laid sufficiently exactly to satisfy the demands of the industry without the use of a reciprocating or oscillating guide eye, the elimination of such element and its operating mechanism is advantageous in reducing noise, preventing certain friction losses, and simplifying the lubrication of the units.

The principal object of this invention is therefore to provide for incorporating in the flexibly connected units of a traveling spindle winding machine traverse devices adapted to distribute the yarn in quick traverse cross-wound formation without the use of a reciprocating or oscillating yarn guiding eye, and to provide for operating such traverse mechanism while the units travel around the guideway of the machine.

Other objects of invention and features of advantage relate to details of the winding unit, some of which are of general application.

In the drawing:

Fig. 1 is a front elevation of a traveling winding unit of the present invention, showing a part of the track or guideway for the several units of the machine;

Fig. 2 is a left elevation of the device of Fig. 1, showing the track or guideway of the machine in vertical section; and

Fig. 3 is a view of the rotary yarn cam of the unit, half in elevation and half in longitudinal section.

The several flexibly connected winding units of the machine are adapted to be conveyed in a

closed path having straight and semi-circular portions in the manner and by the means described in the above patents and in my co-pending applications Serial Nos. 476,776, now Patent No. 2,135,485 and 677,749, now Patent No. 1,993,910. 5

Each unit consists, as shown in the drawing, of a vertical frame piece 11 provided with a roll 12 and pin 13 to guide its lower end on the lower rail 14 of the guideway, and provided at its upper end with a cast head piece 15 having integral 10 opposite vertical side portions 16 and 17 and also carrying rollers 18, 19 and 20 which guide the upper part of the unit on the upper rail 21 of the guideway. The unit is shown as flexibly connected to a conveying chain 22 such as described 15 in the above patents and applications.

The spindle 25 for holding the winding package core 26 is mounted in an arm 27 which is pivoted at 28 on an upward extension 16^a of the side portion 16 of the head of the unit. A wire bail 30, 20 normally pressed away from the observer in Fig. 1, by the running yarn, is adapted to control suitable winding stopping mechanism, including the package lifting rod 31, in the manner described 25 in the above applications, the stopping mechanism also preferably being adapted to lift and lower the package at predetermined places in its path of travel as fully described in the above applications.

Between the upright vertical side portions 16 and 17 there is mounted a rotary yarn traversing element 34 adapted to serve as a friction drive roll for the package formed on the core 26. This traversing and driving element may, for example, take the form of a drum having in its surface a 35 yarn traversing groove 35 which may be shaped according to any of the patterns disclosed in the patents to Colman, No. 1,175,710, Colman, No. 1,274,386, Reece, No. 1,749,355, Bood, No. 1,836,105 or McKean, No. 1,918,210. 40

As shown in Fig. 1, the winding package core 26 initially rests on this grooved drum, so as to be driven thereby. Yarn coming from a bobbin 39, through guide wires 40 and over the bail wire 45 45 38, is then distributed on the core 26 in cross-wound spirals by the grooved drum 34.

The driving means for the drum 34 is preferably in the form of an electric motor, which as indicated in Fig. 3, includes a stationary field 41 50 on the shaft 42 which is held by the side member 16 of the unit, and a rotary armature 43 fastened to the inner surface of the rotary drum 34. Current is supplied to the stationary field 41 by wires 45 from a group of brushes 46 which slide 55

on corresponding stationary conductor bars 47 which extend along the guideway 21.

A switch 48, in series with the wires 45, is provided with an operating handle 49 adapted to be actuated by a projection 50 from the pivoted arm 27, so that when the arm 27 is raised to the height corresponding to the completion of a fully wound package the switch 48 is opened and the motor and drum 34 stopped. This action likewise takes place when the arm 27 is raised by the action of the lifter rod 31, for example when the latter is raised by actuation of the bail wire 30 and the associated stop mechanism of my aforesaid applications.

15 In operation, the several units are conveyed in a procession around the machine. Upon reaching the place at which replenishment operations are conducted, the stopping mechanism of each unit is successively operated by actuation of the 20 lifter rod 31 of the unit, and upon passing the place of replenishment the winding package of the unit is automatically placed in contact with its drive drum 34 and the motor started by means of the rod 31, arm 27 and switch 48, and 25 the lifter rod actuating mechanism of application Serial No. 476,776.

It will be observed that the present invention renders it possible to wind cross-wound packages on the flexibly connected units of traveling 30 spindle winders without resort to the usual reciprocating or oscillating traverse guide eyes. It moreover provides for controlling the several driving and traversing drums individually, so that the individual units are stopped successively for 35 replenishment without stopping the remaining active units, and the drive drums are severally stopped upon the breakage or exhaustion of the strand without stopping the drive drums of the other units.

40 I claim:

1. A multiple traveling unit winding machine having therein a plurality of flexibly connected winding units each including a grooved rotary package driving element adapted to distribute 45 the winding strand on a package, the machine including means for moving the units in a procession around the machine and means for driving the several said rotary elements during travel of the units.
- 50 2. A multiple traveling unit winding machine having therein a plurality of flexibly connected winding units each including a grooved rotary package-driving element adapted to distribute the winding strand on a package, the machine including means for moving the units in a procession around the machine and motors on the

individual units for driving the several said rotary elements during travel of the units.

3. In a winding machine for winding bobbins, a winding unit, a spindle in said unit for mounting the bobbin, rotatable means mounted externally of said spindle and bobbin for rotating said bobbin, an electric motor for imparting rotation to said last-named means, an electric circuit comprising a circuit-making device for energizing said motor, and a thread detector in 10 each winding unit operated by the failure of thread supply to said bobbin for controlling said circuit-making device to break the circuit to said motor and to stop the winding operation.

4. In a winding machine for winding bobbins, 15 a winding unit, a spindle in said unit for mounting the bobbin, a spindle support, rotatable means mounted externally of said spindle and bobbin for rotating said bobbin, an electric motor for imparting rotation to said last-named means, an electric circuit comprising a circuit-making device for energizing said motor, and an adjusting mechanism in each winding unit for controlling the size of the wound bobbin comprising a member extending between the spindle support and said circuit-making device for controlling the latter to break the circuit to said 20 motor at a predetermined position of said spindle support.

5. In a winding machine for winding bobbins, 25 a winding unit, a spindle in said unit for mounting the bobbin, means mounted externally of said spindle and bobbin for guiding the thread onto the bobbin, an electric motor for operating said last-named means, an electric circuit comprising a circuit-making device for energizing said motor, and a thread detector in each winding unit operated by failure of the thread supply to said bobbin for controlling said circuit-making device to break the circuit to said motor and 30 to stop the winding operation.

6. In a winding machine for winding bobbins, 35 a winding unit, a spindle in said unit for mounting the bobbin, a spindle support, means mounted externally of said spindle and bobbin for guiding the thread onto the bobbin, an electric motor for operating said last-named means, an electric circuit comprising a circuit-making device for energizing said motor, and an adjusting mechanism in each winding unit for controlling the size 40 of the wound bobbin comprising a member extending between the spindle support and said circuit-making device for controlling the latter to break the circuit to said motor at a predetermined position of said spindle support.

EDWARD J. ABBOTT.
